UNITED STATES PATENT OFFICE.

WILLIAM F. HENDRY, OF OSSINING, NEW YORK, ASSIGNOR, BY MESNE ASSIGNMENTS, TO NATIONAL CARBON COMPANY, INC., OF NEW YORK, N. Y., A CORPORATION OF NEW YORK.

MACHINE FOR HANDLING ARTICLES.

Application filed February 10, 1926. Serial No. 87,235.

This invention relates to new and useful improvements in machines for handling articles.

It is the object of the present invention to provide a machine by means of which a large number of articles of a fragile nature stored in a reservoir may be delivered automatically in the desired condition. In accordance with the present embodiment of the invention the articles are disc-shaped. They are not assorted in the reservoir, but when discharged therefrom they are advanced in such a manner that only whole articles, and a plurality of them standing on edge side by side, will be deposited in the ultimate receptacle.

In the following a preferred embodiment of the invention will be described in detail. The machine herein disclosed is adapted for delivering into a receptacle four fragile tablets or washers compacted of a mixture of manganese dioxide and graphite, the machine being used in the assembling of dry cells. However, the apparatus may be adapted to advantage for the handling of other articles. The construction may be varied to suit various industrial requirements without departing from the spirit of the invention defined in the appended claims.

In the drawings a tablet or washer assorting machine is illustrated, Fig. 1 being a side elevation; Fig. 2 is a top plan view; Fig. 3 a top plan view on an enlarged scale, as compared with Fig. 2, of the tablet receiving and delivering mechanism; Fig. 4 a plan view of a perforated plate placed below the hopper; Fig. 5 a vertical cross-section of the machine; Fig. 6 a vertical cross-section of a portion of the machine showing the operation of certain gates; Fig. 7 a top plan view of two runway sections; Fig. 8 a vertical cross-section of an intermediate runway section along lines 8-8 of Fig. 5; Fig. 9 a vertical cross-section of the hopper; and Fig. 10 a vertical cross-section of the tablet receiving and delivering mechanism.

The machine as disclosed herein is de-

signed simultaneously to deliver four tablets, standing on edge side by side, into a suitable receptacle such as 2 (Fig. 10). The object is to hold a large supply of unassorted tablets and to deliver only four whole tablets at a time into the receptacle. The tablets are stored in a reservoir or hopper 3 which has a flaring mouth and a sloping bottom 4. The hopper is provided with a side opening near its bottom, as indicated at 5, and through this opening tablets will glide out by gravity between guides 6 and 7 on top of a plate 8. The hopper is pivotally mounted at 10 on a platform 9. The plate 8, as well as the guides 6 and 7, are also mounted on this platform, the rows of small and large perforations 11 and 12 in the plate overlying an opening 13 provided in the platform. The platform 9 is mounted by means of brackets 14 on a table 15 at a suitable angle so as to permit the tablets to gravitate out of the hopper through the opening 5. In order to aid in the emptying of the hopper, the latter is periodically oscillated between the positions indicated in dotted and solid lines, respectively, in Fig. 9, by means of a rod 15^A connected to a bracket 16 of the hopper. The rocking motion is imparted by means of a bell crank lever 17 which is mounted on a shaft 18, the latter being constantly driven through a pulley 19. The shaft 18 is journaled between plates 20 and 76 which are mounted on the table 15.

When tablets fall on the plate 8, some of the dust and small particles will fall out through the openings 11 and 12. In order to keep the tablets within the confines of guides 6 and 7, the hopper 3 is provided with a hood 21 which is suitably mounted on its side and straddles the guides. The plate 8 being inclined, the tablets 1 will glide or roll down this plate onto four runway or chute sections 22, 23, 24 and 25. As best shown in Figs. 5 and 7, each runway like 23 is provided with a bottom sloping down towards the plate and with substantially triangular

guides 24^A. The runways like 23 are slidably held against plate 8 by screws such as 25^A projecting through the bottom of the runway and through slots 26 in the plate 8, into T-shaped blocks 29 engaging the bottom of the plate 8. Two studs 30 project from each block 29 within the slots 26 so as to prevent twisting of the block. During the operation of the machine these runways 10 22 to 25 are caused to oscillate between the positions indicated, respectively, in dotted and solid lines in Fig. 5, so as to cause the tablets near the end of the plate 8 to advance. The manner in which this is accomplished will be explained at a later point.

The width of each runway between the guides is such as to accommodate a tablet standing on its edge. Many of the tablets, however, will lie flat on top of the guides 24^A 20 and between guides of adjacent runways. Special means are provided to insure the proper positioning of these tablets. A bracket 31 projecting from the table 15 rotatably supports above the runways or 25 chutes a shaft 32. Two arc-shaped blades 33 and 34 are mounted on this shaft, one projecting down between runways 25 and 24, and the other between the runways 23 and 22. The blades 33 and 34 are oscillated with 30 shaft 32 between the dotted and full lined positions indicated in Fig. 5, by means of a rod 35 against the tension of a coiled spring 36 stretched between a pin 37 passing through the free end of blade 33 and a pin 38 in bracket 20. One end of rod 33 is fastened to the pin 37, and the other end rides on a circular cam 39 which is eccentrically mounted on shaft 18. The vertical and lateral displacements of rod 35 being prevented 40 by a bracket 40 mounted on plate 20, during the rotation of shaft 18 the rod will longitudinally oscillate and cause blades 33 and 34 to move back and forth between the chutes. In order to permit free movement of the 45 blades 33 and 34, slots 41 and 42 are provided in the plate 8 so that the blades register therewith. The relative proportions of the tablets and the chutes are such that if a tablet lies on any guide wall 24^A, then it will be tipped over by one of the oscillating blades so that it falls edgewise on one of the chutes. Only properly positioned tablets 50 can therefore pass beyond the blades 33 and 34, and from this point on the tablets will roll or glide edgewise on the chutes.

As the tablets roll between the blades 33 and 34, fragments such as 43 will be dropped from the chute. This is accomplished by the operation of gates such as 44. Each 60 chute section 22-25 is provided near its end with a gate like 44, the gate being pivotally mounted on the chute at 45. The gate swings within an opening 46 in the chute. While the chutes 22-25 are moving to the left 65 from their extreme right-hand positions,

each gate rests on plate 8 in alignment with one of the slots 26, the width of the gates being greater than that of slots 26. As indicated in Fig. 6, the plate 8 will keep the gates 44 closed and the tablets will roll over them. When, however, a chute section reaches its extreme left-hand position, then, owing to the provision of an enlargement 47 at the end of each slot 26, the gate 42 is permitted to drop down into the position illustrated in Fig. 5. Small sized fragments of tablets will now drop down from the chutes through the openings 46.

Tablets that roll over the gates 44 of the chute sections 22-25 reach a second runway section. Four such sections 48, 49, 50 and 51 are provided, each constituting a continuation of one of the chutes 22-25. The chute sections 22-25 and 48-51 are pivotally joined together by means of shafts such as 52, 53, etc. As was the case with the first group of sections, chutes 48-51 are also provided with guide walls 54 confining the tablets to an upright position. The guide walls 54 are held together below the runways by means of rods such as 54^A. As a tablet enters a section 48-51, it first passes over a gate 55. The gates 55 are pivotally mounted in the runways at 56 within openings 57 which are wide enough to insure the dropping through of tablet fragments like 58 (Fig. 6) which passed over the opening 46.

The gates 55 are periodically opened and closed during the operation of the machine in the following manner: A bell-crank lever arrangement 60 engages the lower end of the gate 55 at 61. This bell crank lever 60 is mounted on a plate 62. One plate like 62 is provided below each chute section 48 to 51 and each of these plates is provided with a lever arrangement like 60 for controlling the gate 55 of the respective chute. The plate 62 of each chute section may be oscillated with respect to the chute itself in a manner to be hereinafter described, and during this motion, the gate 55 is moved from the position indicated in Fig. 5 into the position illustrated in Fig. 6, to test the size of the tablet that happens to rest thereon. The plate 62 is provided with two perforations 63 and 64 which, in the position illustrated in Fig. 5, register with perforations 65 and 66 provided in the runway. While the plate 62 and the runway are longitudinally displaced with respect to each other, the openings in these two will be alternately brought into registry, or the openings in the runway will coincide with the solid portions of plate 62. The extremes of this relative displacement are illustrated in Figs. 5 and 6, respectively. The side walls of the openings 65 and 66 are sloping, the entrance of each opening being large enough to permit the passage there-

through of a whole tablet. The diameters of the openings 63 and 64 are equal to the base of the openings 65 and 66, which is such that a whole tablet cannot drop through it, but tablets with parts chipped off, such as 67 and 68, will drop through. In this manner it is insured that only whole round tablets will roll past the opening 66 in each runway section 48 to 51. Having cleared this 10 gauge, the tablets roll or slide to the end of the runway section and from there enter into runway sections 70, 71, 72 and 73. Near the left-hand end of each runway 70 to 73, a boss like 74 is provided through which a 15 shaft 75 projects, the ends of which are journaled in the brackets 20 and 76 projecting from the table 15. Each runway may be moved up and down around this shaft as a pivot point. On the runways 70 to 73, the 20 tablets are confined into an upright position by means of guide walls such as 77. The walls 77 are held together below the runways by studs 77^A. These guide walls, as well as the guide walls 54 of the chute sections 48 to 51, form arc segments and extend above and below their respective runways. The 25 arc-shaped right-hand end of each guide 77 is toothed, as indicated at 78, and these teeth intermesh with the teeth 79 formed in the 30 arcuate ends of the guide plates 54 of the preceding chute section. A lug 80 downwardly projecting from the guide plate 77 carries a roller 81 which rides within a groove 82 provided in the side of a circular cam 83. The cam 83 is eccentrically mounted on the shaft 18 and during its rotation, indicated by the arrow (Fig. 5), it will cause the guides 77 with chute 71 to rock around the pivot point 75. The guides 35 of chutes 71 and 73 are connected each with a cam like 82 and therefore these two guides will be rocked in unison. On the other hand, the guide plates of chutes 70 and 72, e. g., 77^B, are provided with lugs 40 like 80^A, the rollers 81^A of which ride in a groove 84 of the circular cam 39 (one cam being provided for each of said chutes) which are angularly displaced by 180° with 45 respect to the cams 82. The chutes 70 and 72 will be also rocked around shaft 75, but will reach their lowermost positions when the chutes 70 to 73 are in their uppermost positions. This rocking of the chutes 70 to 73 will cause the advance of the tablets and will 50 tend also to shake down into line tablets that may have crowded on top of other tablets or that may be lying on the guideways 77. Furthermore, through the gear teeth 78, 79, the rocking motion of the chutes 55 will be transmitted to the chute sections 48 to 51, and through a lever arrangement 85 (one being provided for each chute section) to the plates 62, causing thereby the reciprocation of these plates and the associated 60 gates 55. The chute sections 48 to 51 will

be oscillated back and forth between the positions indicated in dotted and solid lines, respectively, in Fig. 5, and cause in turn the oscillation of the chute sections 22 to 25 with the above described results. The oscillation of these chute sections will tend to stir up the tablets at the bottom of the hopper, will cause the advance of the tablets, and insure that broken tablets drop through gates 44 and 45 and openings 65 and 66. 70 75

In order to insure that the guides 77 and 54 remain properly in mesh, springs may be employed against the resiliency of which the parts are operated. However, such springs have been found troublesome owing to the fact that they lose their resiliency and that if they are sufficiently stiff, the power consumption is too high. Furthermore, such springs easily get out of alignment and tangled. In order to obviate this, one end 80 of a rod 86 is pivoted at 87 between each pair of guide plates 54. The other end of said rod is pivotally connected at 88 with the free end of a lever 89. This lever is pivoted on a stud 90 mounted on an ear 91 of the bracket 20 projecting within an opening 92 of the table 15. The lever 89 is provided with a cam surface 93. A roller 94 mounted on the end of a lever 95 rides over this cam surface 95 when the lever 95 is rocked around a shaft 38 on which it is mounted. An ear 96 of lever 95 carries a roller 97 which rides in the groove 82 of cam 83 at a point diametrically opposite to that occupied by the roller 81. The lever 95 will therefore be in its uppermost position, illustrated in Fig. 5, when the chutes 70 to 73 are in their uppermost position, and the cams 83 will move the levers 95 up and down in unison with the chutes 71 and 73. During the movement of 100 the roller 94 on the cam surface 93, the lever 89 is permitted gradually to move to the right until it reaches the position indicated in Fig. 6, permitting therefore a corresponding right-hand displacement of the associated chute sections 49 and 51. The levers are so proportioned and the cam surface 93 so cut that the gear teeth 78 and 79 are constantly maintained in mesh. Similarly, the chute sections 70 and 72 are interconnected by 105 means of rods 86^A which, through levers 89^A and 95^A are operated by their cams 39 half a cycle behind the two other chute sections. 110

Tablets positioned in the runways 70 to 73 will roll onto a platform 100. The platform 100 is mounted on the brackets 20 and 76 by means of triangular plates 101, 102, and the entrance of tablets to this platform is controlled by a wedge shaped plate 103 in which a cover 104 of the platform 100 terminates. 120 The plate 103 is provided with notches such as 105 coinciding with the runway, and only tablets rolling on the runways will be able to pass through these notches onto said platform. Tablets that roll on top of other 125 130

tablets or that lie on the guide walls will hit against the plate 103 and fall off the machine into a suitable receptacle. As clearly illustrated in Figs. 5 and 10, the platform 100 will, during the operation of the machine, contain three rows of tablets (each row comprising four tablets) confined between the platform 100, its cover 104 and the side plates 106 and 107.

10. A tilttable tablet receiver 110 is pivotally mounted on the end of the platform 100 by means of a shaft 111. A coiled spring 112 stretched between shaft 75 and a pin 113 projecting from a side wall of the receiver 110 normally holds the latter in the position illustrated in Figs. 1 and 5. The receiver is open on top and it is longitudinally divided into four sections by means of converging dividing walls 114, 115 and 116. 15. The bottom of the receiver 110 is at one end curved up as indicated at 117. The first row of tablets on the platform 110 will roll within this curved-up end of the receiver, one tablet being confined within each runway 20. defined by the dividing walls 114 to 116. When it is desired to deposit a group of four tablets in the receptacle 2, then by suitable means the receiver 110 is tilted down against the tension of spring 112 into the position 25. illustrated in Fig. 10, whereupon the four tablets will roll down to the end of this receiver and drop out through the opening 118, being guided thereto by the walls 114 to 116 and a guard 119 provided at the end 30. of the receiver. While the receiver is in this tilted-down position, the curved-up end 117 (see Fig. 10) prevents the first row of tablets on platform 100 from advancing.

What is claimed is:

40. 1. In a machine of the class described, a reservoir for articles of uniform size and shape, runways leading to said reservoir, and means comprising intermeshing gear sectors attached to said runways for oscillating said runways with respect to each other and to said reservoir to cause the advance of said articles on said runways.

45. 2. In a machine of the class described, a reservoir for articles of disc shape, runways leading to said reservoir, guides for confining said articles on said runways in an upright position, a receptacle, and a tilttable conveyor means for depositing from each runway only one article at a time in said receptacle.

50. 3. In a machine of the class described, a reservoir for articles of uniform size and shape, a runway into which said reservoir empties, said runway being divided into two sections, a constantly rotating shaft, means controlled by said shaft for oscillating the first section, and means jointly controlled by said shaft and first section for oscillating the second section and longitud-

inally displacing it with respect to said reservoir.

4. In a machine of the class described, a reservoir for articles of uniform size and shape, a runway into which said reservoir empties, said runway being divided into three sections, a constantly rotating shaft, a cam controlled by said shaft for oscillating the first section, means controlled by the first section and said cam for oscillating the second section and longitudinally moving it with respect to said first section, means controlled by the second section for longitudinally moving said third section with respect to said reservoir, and a lever operated by said shaft for oscillating said reservoir with respect to said runway.

5. In a machine of the class described, a reservoir for articles of uniform size and shape, a plurality of runways arranged side by side into which said reservoir empties, each of said runways being divided into first, second and third sections, a constantly rotating shaft, means controlled by said shaft for oscillating said first sections with respect to each other, means jointly controlled by said first sections and said shaft for oscillating said second sections with respect to each other, means controlled by said second sections for longitudinally moving said third sections with respect to each other and said reservoir, and a lever operated by said shaft for oscillating said reservoir with respect to said runways.

6. In a machine of the class described, a reservoir for articles of uniform size and shape, a plurality of runways arranged side by side into which said reservoir empties, each of said runways being divided into first, second and third sections, a constantly rotating shaft, cams controlled by said shaft for oscillating said first sections with respect to each other, means jointly controlled by said first sections and said cams for oscillating said second sections with respect to each other and longitudinally moving them with respect to said first sections, means controlled by said second sections for longitudinally moving said third sections with respect to each other and said reservoir, and a lever operated by said shaft for oscillating said reservoir with respect to said runways.

7. In a machine of the class described, a reservoir for articles of uniform size and shape, a runway into which said reservoir empties, said runway being divided into a first and a second section, a constantly rotating shaft, cams operated by said shaft simultaneously to oscillate in a vertical direction said sections, and a lever operated by said cam longitudinally to oscillate said second section in proportion with said oscillation in a vertical direction.

8. In a machine of the class described, a reservoir for articles of uniform size and shape, a plurality of runways arranged side by side and into which said reservoir empties, each of said runways being divided into a first and a second section, the opposing ends of said sections being arc-shaped and provided with intermeshing gear teeth, a constantly rotating shaft, a stationary shaft on which said first sections are pivotally mounted near one end, cams actuated by said shaft to oscillate said first sections around their pivot point in different order, and levers controlled by said cams for longitudinally displacing said second sections in proportion with the oscillating movement of said first sections.

9. In a machine of the class described, a reservoir for articles of uniform size and shape, a plurality of runways arranged side by side and into which said reservoir empties, each of said runways being divided into a first and a second section, the opposing ends of said sections being arc-shaped and provided with intermeshing gear teeth, a constantly rotating shaft, two cams mounted on said shaft at an angular displacement with respect to each other, a stationary shaft on which said first sections are pivotally mounted near one end, a connection between each of said first sections near the other end and said cams, respectively, two pivoted levers, rods connecting the free ends of said levers with the arcuate ends of said second sections, a cam surface on each lever, two pivoted levers engaging, respectively, said cam surfaces, and a connection between each of said last mentioned levers and said cams, respectively.

10. In a machine of the class described, a reservoir for articles of uniform size and shape, a plurality of runways arranged side by side and into which said reservoir empties, each of said runways being divided into a first and a second section, guide plates for each section arranged to maintain the articles on said runways in a certain position, the opposing ends of said guides being arc-shaped and provided with intermeshing gear teeth, a constantly rotating shaft, two circular cams eccentrically mounted on said shaft at an angular displacement of 180° with respect to each other, a circular groove in each cam, a stationary shaft on which said first sections are pivotally mounted near one end, a roller projecting from each of said first sections near the other end, said rollers engaging the grooves of said cams, respectively, two pivoted levers, rods connecting the free ends of said levers with the arcuate ends of the guides of said second sections, a cam surface on each lever, two pivoted levers engaging, respectively, said cam surfaces, and a roller carried by each of said last mentioned levers engaging, re-

spectively, the grooves on said circular cams at points diametrically opposite the points engaged by said first mentioned rollers.

11. In a machine of the character described, a reservoir for articles of uniform size and shape, said reservoir having an opening, a plate provided with a plurality of holes provided below said opening, a runway leading to said plate, and means for longitudinally oscillating said runway with respect to said plate.

12. In a machine of the character described, a reservoir for articles of uniform size and shape, said reservoir having an opening, a plate provided with a plurality of holes provided below said opening, a plurality of runways slidably mounted on said plate, and means for longitudinally oscillating said runways with respect to each other and said plate.

13. In a machine of the character described, a reservoir for articles of uniform size and shape, said reservoir having an opening through which a number of said articles may be discharged, a bottom for said reservoir sloping towards said opening a plate provided with a plurality of holes of different sizes provided below said openings, a runway of wedge-shaped cross-section slidably mounted on said plate, and means for longitudinally oscillating said runway with respect to said plate and for oscillating said reservoir.

14. In a machine of the character described, a reservoir for articles of uniform size and shape, a runway, a plate having a plurality of openings between the end of said runway and said reservoir, a constantly rotating shaft, mechanism for oscillating said runway, a plurality of gauges in said runway, and means jointly controlled by said mechanism and runway for opening and closing said gauges.

15. In a machine of the character described, a reservoir for articles of uniform size and shape, said reservoir having an opening through which said articles may be discharged, a runway divided into two sections, a plate having a plurality of openings of different sizes between the end of said runway and the opening in said reservoir, means for slidably mounting the end of one of said runway sections on said plate, means for pivotally joining together said two runway sections, a constantly rotating shaft, mechanism for oscillating in a vertical direction one of said sections and in a longitudinal direction both sections, a gate in one of said sections periodically opened in response to the longitudinal oscillation thereof, and a second gate and a plurality of gauges in the other section periodically opened in response to the longitudinal displacement thereof.

16. In a machine of the character described, a reservoir, a runway into which

8
said reservoir opens, said runway being provided with a bottom having a plurality of openings, a plate provided below said bottom having a plurality of openings registering with the openings in said bottom, and means for longitudinally displacing said plate with respect to said runway.

17. In a machine of the character described, a reservoir, a runway into which said reservoir opens, said runway being provided with a bottom having a plurality of openings, a plate provided below said bottom having a plurality of openings registering with the openings in said bottom, mechanism for oscillating in a vertical and longitudinal direction said runway with respect to said reservoir, and means controlled by said mechanism for longitudinally displacing said plate with respect to said runway.

20 18. In a machine of the character described, a reservoir, a runway into which said reservoir opens divided into a first and a second section, said second section being provided with a bottom having a plurality of openings, a gate covering one of said openings, a plate provided below said bottom having a plurality of openings registering with some of the openings in said bottom, a bell crank connection between said plate and the first section, a bell crank connection between said gate and said plate, and mechanism for oscillating in a vertical direction said sections and longitudinally displacing said second section with respect to the first section.

19. In a machine of the character described, a reservoir for articles of uniform shape and size, runways leading to said reservoir and through which a plurality of said articles may be simultaneously carried away therefrom, guides for each runway section confining an article thereon in a predetermined position, the greatest width of said articles being greater than that of a runway, and means for sweeping off the guides onto said runways articles that lie on said guides.

20. In a machine of the character described, a reservoir for articles of uniform shape and size, runways leading to said reservoir and through which a plurality of said articles may be deposited in a receptacle, said runways being divided into a plurality of sections, guide plates for each runway section confining an article thereon in a predetermined position, mechanism for oscillating said runway sections and reservoir with respect to each other, mechanism mounted near said reservoir for moving articles positioned on said guide walls onto the runways within said guide walls, and a common source of power from which both said mechanisms are operated.

21. In a machine of the character described, a reservoir for articles of uniform shape and size, runways leading to said res-

ervoir and through which a plurality of articles may simultaneously be deposited in a receptacle, blades projecting between said runways near said reservoir, and means for oscillating said blades.

22. In a machine of the character described, a reservoir for articles of uniform shape and size, runways leading to said reservoir and through which a plurality of said articles may be simultaneously carried away therefrom, said runways being divided into a plurality of sections, guides for each runway section confining an article thereon in a predetermined position, a constantly rotating shaft, mechanism operated by said shaft for oscillating said sections, plates projecting between the guides of adjacent runways, and means controlled by said mechanism for continuously oscillating said plates.

23. In a machine of the character described, a reservoir for articles of uniform shape and size, runways leading to said reservoir and through which a plurality of said articles may be simultaneously carried away therefrom, said runways being divided into a plurality of sections, guides for each runway section confining an article thereon in a predetermined position, a constantly rotating shaft, mechanism operated by said shaft for relatively oscillating two sections in a vertical direction and two sections in a longitudinal direction and for oscillating said reservoir, plates projecting between guides of adjacent runways, and means controlled by said mechanism for continuously oscillating 100 said plates.

24. In a machine of the character described, a reservoir for articles of uniform size and shape, a plurality of runways into which said reservoir discharges, means for advancing said articles over said runways, a receptacle for a number of said articles, a platform at the end of said runways, and a tiltable trough-like guide mounted on the end of said platform for depositing in said receptacle one article from each runway and arresting the other articles on said runway.

25. In a machine of the character described, a reservoir for articles of uniform shape and size, a plurality of runways into which said reservoir discharges, means for advancing said articles over said runways, an inclined platform at the end of said runways, a guard between said platform and runways having notches registering with the runways for allowing but a single article at a time to pass from a runway to said platform, a receptacle for a number of said articles below the end of said platform, and mechanism for delivering to said receptacle 120 from said platform only said number of articles at a time.

26. In a machine of the character described, a reservoir for articles of uniform size and shape, a plurality of runways into 130

which said reservoir discharges, means for advancing said articles over said runways, a platform at the end of said runways, a V-shaped guard between said platform and runways having notches registering with the runways, and a receiver pivotally mounted on the end of said platform and provided with a bottom open on the free side of said

receiver and curved up on the other side to act as a stop for articles on said platform 10 while said receiver is in a tilted-down position.

In testimony whereof, I have signed my name to this specification this eighth day of February, 1926.

WILLIAM F. HENDRY.
